CLAIM

(21) Appl. No.: **29/474,869**

The ornamental design for a decorative hinge for a vehicle tool box, as shown and described.

(22) Filed: **Mar. 2, 2015**

DESCRIPTION

(51) **LOC (10) Cl.** **12-99**

FIG. 1 is a top side perspective view of a decorative hinge for a vehicle tool box;

(52) **U.S. Cl.**

FIG. 2 is an enlarged bottom perspective view of a decorative hinge for a vehicle tool box;

USPC **D12/414.1**

FIG. 3 is a bottom side perspective view of a decorative hinge for a vehicle tool box;

(58) **Field of Classification Search**

FIG. 4 is an end view of a decorative hinge for a vehicle tool box;

USPC D12/414.1, 414, 413, 412, 221,

FIG. 5 is a top plan view of a decorative hinge for a vehicle tool box; and,

D12/406.157, 423; D6/552, 317-319,

FIG. 6 is a rear plan view of a decorative hinge for a vehicle tool box;

D6/513-514; D3/304-306; D32/35, 58

The breaks in the drawing figures show no specific length.

CPC B60R 7/02; Y10S 224/925

In the drawings, the broken lines show a vehicle and portions of a tool box that form no part of the claimed design.

See application file for complete search history.
